SHERMAN E. ANTHONY, OF STILLWATER, NEW YORK.

Letters Patent No. 62,990, dated March 19, 1867.

IMPROVEMENT IN SHINGLE MACHINES.

The Schedule referred to in these Letters Patent and making part of the same.

TO ALL WHOM IT MAY CONCERN:

Be it known that I, SHERMAN E. ANTHONY, of Stillwater, in the county of Saratoga, and State of New York, have invented a new and improved Shingle Machine; and I do hereby declare that the following is a full, clear, and exact description thereof, which will enable others skilled in the art to make and use the same, reference being had to the accompanying drawings, forming part of this specification, in which—

Figure 1 is a side sectional view of my invention, taken in the line $x x$, fig. 2.

Figure 2, a plan or top view of the same.

Figure 3, a transverse vertical section of the same, taken in the line $y y$, figs. 1 and 2.

Similar letters of reference indicate like parts.

This invention relates to a new and improved shingle machine, of that class in which a circular saw is used for cutting the shingles from the bolt; and it consists of a series of disconnected bolt-carriages, arranged to work in suitable guides, and in such a manner as to form, without hinges, links, or any connection whatever, an endless chain of carriages. The invention also consists in an improved mechanism for dogging and undogging the bolts, all arranged substantially as hereinafter fully shown and described.

A represent the two sides of the framing of the machine, which may be of cast iron, and having semi-circular ends. The inner surfaces of these side pieces are cast with a groove or recess, a , all around, near their edges, (see fig. 3,) and in these grooves friction-rollers b , at the ends of bolt-carriages B , are fitted and allowed to work freely. The bolt-carriages B are of rectangular form, of cast iron, and they are fitted between the side pieces A of the framing, in contact with each other, so as to form an endless chain of carriages all around the framing, and without being connected by hinges or joints of any kind. This endless chain of carriages is moved by means of teeth c , on disks or wheels $d d$, on a shaft, C , in one end of the framing, the teeth of the two disks or wheels acting against lugs or projections e , at each end of the carriages; and it will be seen that if one carriage be moved the whole will be moved. By this arrangement I avoid the use of hinges or joints for connecting the carriages, thereby saving considerable in the manufacture of the machine, as well as avoiding friction. D is a circular saw, placed on the upper end of a vertical shaft, E , in the machine, the saw being directly underneath the upper part of the endless chain of carriages. The carriages B are rectangular frames, each being provided with a sliding-dog, F , serrated or toothed at its lower part, and provided at its upper part with a horizontal arm, f , which is fitted and allowed to work or freely move in one of the end pieces of the carriages B , the outer ends of the arms f being turned upward to form a lip, g , to catch under a diagonal flange, h , on a plate, G , attached to the upper part of the framing. The lips g of the arms f pass behind this flange h as the endless chain of carriages is moved, and the dogs F are thereby drawn back out of the ends of the bolts, the latter being held or prevented from being drawn back out of the bolt by means of a fixed plate, i , which passes through the dogs F . H is a screw, which is fitted vertically in a nut or female thread in the ends of the carriages in which the arms f work. The screws H have T-heads, j , on them, and the plate G has an upright pin, k , upon it, and also a curved plate, I , attached. The screws H are for the purpose of holding the dogs F in the bolts or preventing them from moving casually, said screws acting or pressing upon the arms f , and to admit of the dogs F being drawn out from the ends of the bolts, as described. The screws are turned by one end of the heads j coming in contact with the upright pin k , on the plate G , and after the dogs are drawn back to free the bolts, and the latter drop upon the lifting-bed O , hereinafter described, the dogs F are forced into the ends of the bolts, in consequence of the lips g of the arms f coming in contact with a spring, K , on plate G , the screws H being turned down to press upon the arms f by the plate I , against which the heads j come in contact. The dogs L , at the opposite ends of the bolt-carriages, are fixed or stationary, and provided with serrated or toothed edges. The bolts are freed from these dogs L by means of sliding-bars M , which have arms l attached, the latter passing through the end pieces of the carriages and turned upward at their outer ends to form lips which come in contact with the bevelled end of a plate, N , on the framing, said bevelled end forcing the bars M forward so as to shove the ends of the bolts free from the dogs L as the dogs F at the other ends of the bolts are drawn out from them. The bolts, which are shown in red in figs. 1 and 3, drop upon a tilting-bed, O , when freed from the dogs, and this tilting-bed causes the shingles to be sawed from the bolt in taper form, the bolts being undogged and set by the bed O previous to coming in

contact with the saw. The bed O is simply a rectangular frame, fitted on a central shaft, m, and resting at one end on a toothed wheel, n, the shaft n* of which has a circular disk, P, upon it, provided with teeth o. This disk P is rotated by the endless chain of carriages as they are moved along, and the toothed wheel n raises and inclines the bed O in one position by its teeth catching or acting against a rod, o*, projecting from said bed, the bed being inclined in the opposite direction when the rod o* drops between the teeth of the wheel n. A tooth of the wheel n comes under and acts upon the rod o* at every alternate movement of the wheel n, the rod o* dropping between the teeth at the intermediate movements. The bed O may be made to tilt at a greater or less angle by adjusting the wheel n on its shaft n* nearer to or further from the shaft m of the bed O. The tilting of the bed O, so that it will be inclined consecutively in opposite directions, causes the shingles to be sawed in proper taper form.

I do not claim the tilting-bed O, for that is an old and well-known device; but I do claim as new, and desire to secure by Letters Patent—

1. The disconnected bolt-carriages B, with projections e, operating with the toothed wheels d, substantially as described for the purpose specified.
2. The operating of the sliding-dogs through the medium of the T headed screws H, flanged spring plate G, pin k, arm f, and lip g, substantially as described for the purpose specified.
3. The fixed or stationary dogs L, in connection with the sliding-bars M, and the plates N, on the framing, having bevelled or diagonal ends, substantially as shown and described.
4. The fixed plate t, in combination with the slotted dogs F, substantially as and for the purpose specified.

SHERMAN E. ANTHONY.
